TRIPLE DRESSER

Ernest Herrmann, Hillsdale, N. J., assignor to Heywood-Wakefield Company, Gardner, Mass., a corporation of Massachusetts

Application March 14, 1955, Serial No. 35,038

Term of patent 7 years

(Cl. D33—6)

Fig. 1.

Fig. 2.

Fig. 3.

Fig. 4.

Fig. 1 is a front perspective view of a triple dresser embodying my new design;

Fig. 2 is an enlarged fragmentary cross section taken on the line 2—2 of Fig. 1;

Fig. 3 is an enlarged fragmentary cross section on the line 3—3 of Fig. 1; and

Fig. 4 is an enlarged perspective view illustrating one of the drawer pulls in detail, the concave front thereof stippled to indicate contrast.

I claim:

The ornamental design for a triple dresser, substantially as shown and described.
